LIGHT SIGNAL

Salisbury M. Day, Rochester, N. Y., assignor to
General Railway Signal Company, Rochester,
N. Y.

Application March 2, 1925, Serial No. 12,582

2 Claims. (Cl. 177—329)

This invention relates to wayside signals for railways and more specifically concerns a color light wayside signal embodying light concentrating means of the reflector type.

5 Color light signals for use in railway signal work are designed to project a concentrated light beam along the trackway, the color or other aspect of this light being an indication of the traffic conditions ahead. It is desirable that such 10 a signal may project a beam which is clearly distinguishable at a comparatively long range, such as 3000 or 4000 feet, even by daylight under the most unfavorable conditions of light and background, and that the energy consumption of 15 the signal be a minimum. It is also desirable to provide for a ready inspection of the light-projecting unit in order that it may be easily and quickly cleaned, repaired and focused.

With the above and other considerations in 20 mind, it is proposed in accordance with the present invention to provide a color light signal of the type employing a combined reflecting and refracting means which will utilize a maximum amount of the light emerging from the light 25 source, and to provide a mounting for this reflecting means and light source which will facilitate the inspection and maintenance of such reflecting means and source, and will permit relative adjustment of the source and the reflecting 30 means for focus.

Other objects and advantageous features of the present invention will become apparent as the description thereof progresses.

In describing the invention in detail, reference 35 will be made to the accompanying drawings, in which:—

Fig. 1 shows a sectional side view of the light signal embodying the present invention together with a supporting means therefor;

40 Fig. 2 shows a rear view of the signal with the door removed, certain portions of the device being broken away for clearness;

Fig. 3 is a section taken on the line 3—3 of Figs. 1 and 2, viewed in the direction of the 45 arrows;

Fig. 4 is a section taken on the line 4—4 of Fig. 2, viewed in the direction of the arrows;

50 Fig. 5 is a sectional side view of a modified form of the mirror supporting means for the light signal of the present invention; and

Fig. 6 is a section taken on the line 6—6 of Fig. 5 and viewed in the direction of the arrows.

55 Referring to the drawings, the light signal comprises the usual casing C provided with a large opening 2 in its front face and small openings 3

and 4 in its top and bottom walls respectively. The casing C may be secured to any suitable support, and for the purpose of illustration has been shown mounted on a cap member 5 which is adjustably secured to a signal post or other suitable structure 6 by means of the set screws 7, the casing C being adjustably secured to the cap member 5 by means of the bolts 8 in a manner which is readily apparent from the drawings. A rear cover or door 9 is provided on the casing C, being secured in place by suitable hinges 10, and a hasp 11, and being provided with a gasket 12, carried in a groove at the edge of the door 9 and adapted to seat tightly against the edges of the casing C in order to insure a moisture-proof closure. The door 9 is provided with a ventilating opening 13 which is protected by a cap or shield 14 and a screen 15 as shown.

When two or more casings are connected together to form a signal unit, the small openings 20 3 and 4 are used to conduct the wires for the light bulb from one casing to another, and the openings which are not so used may be covered by a plate 16, secured to the casing over these holes by the bolts 8 as shown.

25 A supporting structure S for the light projecting unit is secured to the casing C at the large opening 2 in its front wall. This structure S comprises an outwardly projecting tubular portion 19 having a circular opening 20 and carrying a 30 flange 18, and a rearwardly projecting shelf portion 21. The structure S is secured to the casing C by means of the bolts 11 passing through holes in the flanges 18 as shown. An outer lens or color 35 screen 22, comprising a plain glass having a distinctive color or other aspect is fitted at its edges in a rabbet or groove 23 in the opening 20 of the structure S, the color screen 22 being held in place by the ring 24 and the screw bolts 25. A shield 40 or hood 26 is secured to the structure S over the lens 22 as shown, and acts to shade this lens from sunlight and to provide a shaded background around the lens and thus to make the signal more clearly distinguishable in the daytime.

45 The light projecting unit consists of two elements, a concave reflecting and refracting mirror 21, and an incandescent light bulb 28, which are secured to the supporting structure S by means of a bracket B. This bracket B is of irregular shape as most clearly shown in Fig. 1, having a 50 horizontal base portion 29 and a rear wall 30, a portion of this wall 30 being arranged at an angle to the vertical as shown at 31. The bracket B is secured to the shelf portion 21 of the supporting structure by means of the screws 32 as shown. 55

Two ears 33 extend upwardly from the side walls 34 of the bracket B, and are provided with aligned horizontal openings. A mirror frame 35, provided with integral ears 36 is pivoted to the bracket B by means of the bolts 37 passing through openings in the ears 33 and 36, the ears 36 being provided with integral stop projections 38 which are arranged to engage the rear wall 30 of the bracket B and so limit the movement of the frame 35. 10 The frame 35 is rabbeted to receive the edges of the mirror 27 which is held in the frame by the clips 39 and the screws 40 as shown.

Two spring latches 41 are secured to the opposite side walls 34 of the bracket B by means of 15 the screws 42, the free ends of these latches extending above the walls 34 and being bent outwardly as clearly shown in Fig. 2. Small pins 43 (see Fig. 4) extend horizontally from opposite 20 edges of the frame 35, and when the frame is in its vertical position, these pins engage corresponding holes in the latches 41, thus latching the frame 35 in its operative position. When it is desired to tilt the frame 35 backward for cleaning, replacing the lamp, or inspecting the mirror, 25 the spring latches 41 are drawn outwardly, releasing the pins 43 in the frame 35, and permitting the frame to be swung to a horizontal position about the bolts 37.

The light bulb 28 is supported within the mirror, 30 27, on an adjustable base D, the filament of the bulb 28 being arranged near the focal point of the mirror. The base D has a forked extension 44 which rests upon the lower face of the cylindrical portion of the supporting structure S, straddling an eye bolt 45 as clearly shown in Figs. 1 and 3. An adjusting screw 46 is rigidly secured 35 to a vertical extension 47 of the base D and extends rearwardly through a vertical straight slot 48 (Figs. 1 and 3) in the wall 31 of the bracket B. A plate 49 is adjustably secured to the rear wall 31 of the bracket B by a thumb screw 50 passing through a horizontal straight slot 51 (Figs. 2 and 4) in this plate as shown, and the 40 adjusting screw 46 passes snugly slidably through a circular hole in the plate 49 and is provided with a wing nut 52. A coiled spring 53 is connected 45 between an angular vertical extension 54 of the base D and the eye bolt 45, and acts to urge the base D forward, drawing the wing nut 52 against the plate 49. By turning the wing nut 52, the base D may be moved in a horizontal plane against the pull of the spring 53, and by loosening the thumb screw 50, the plate 49 may be shifted on the bracket B in a direction parallel with vertical slot 48 while turning on screw 50 as a slidably pivot in horizontal slot 51 to any position within the limits of the slots 48 and 51, so moving the adjusting screw 46 and the base D in a substantially 50 vertical plane.

A light socket support 55 is secured to insulating posts 56 on the vertical extension 54 of the base D as shown. The upper end of the support 55 is bent into semi-circular shape and is soldered, welded, or otherwise suitably secured to a lamp socket 57 which is thereby held in a horizontal position. The central contact of the socket 57 is provided with a suitable connector 58, and a wire 59 is electrically connected to the support 55 by a screw 60. The wires for supplying energy 65 to the light bulb have been shown broken away, but it is assumed that these wires will pass through the opening 4 in the lower wall of the casing C, through the hollow cap 5 and the signal post 6 to some suitable circuit controlling means and 70 source of energy.

The mirror 27 is of the combined reflecting and refracting type, and as the particular construction of this mirror forms no part of the present invention, only a brief description of its structure and operation will be given. The mirror is semi-spherical in form and is mirrored on its rear or convex surface so that the light passes through the glass before being reflected. The glass is of varying thickness as shown, and is so arranged with respect to the filament of the light bulb 28 10 that the light emerging from this filament is concentrated into a well defined beam. It should be particularly noted that the shape of the mirror 27 and the location of the light bulb 28 within it are such that a large spherical angle of the light 15 emerging from the filament of the bulb is utilized, and for this reason the light projecting unit is very efficient.

In order to obtain the maximum efficiency from a light projecting unit of this type, the filament 20 of the light bulb 28 must be properly focused with respect to the mirror 27. In order to facilitate this adjustment, focus markers 61 are provided near the edges of the outer lens or color screen 22. These focus markers may consist of short radially 25 spaced parallel lines painted on the inner surface of the color screen 22, or small strips of paper or other suitable material having parallel lines marked thereon may be glued or otherwise 30 suitably secured to this surface, or may be secured to the ring 24 by means of rivets as shown, three of these markers being provided at substantially equally spaced points around the edge of the color screen 22. The parallel lines on the markers 61 are equally spaced from the axis of 35 the color screen 22, and the light bulb 28 is moved in a vertical plane by the adjustment means described above until the edges of the light beam co-incide with corresponding lines on all three of the markers 61. The size of the beam 40 may now be adjusted by moving the light bulb 28 toward or away from the mirror 27 by means of the wing nut 52. In this manner, the light beam 45 may be quickly and accurately focused.

In Figs. 5 and 6, a modified form of support- 45 ing means for the mirror 27 has been shown, this modification including a means for adjusting the position in which the mirror supporting frame 35 is held when in its operating position. In this modification, the rearwardly projecting shelf por- 50 tion 21 of the supporting structure S carries a bracket B' which is slightly different in construction from the bracket B of the form shown in Figs. 1 through 4, the bracket B' having an ex- 55 tended base portion 63 provided with two up- 60 wardly extending bosses 64 at its sides as clearly shown in Fig. 6. These bosses 64 are arranged directly under the position occupied by the front edge of the mirror frame 35 when in its upright 65 position, and carry set screws 65 provided with lock nuts 66, the heads of the set screws being arranged to act as stops for the frame 35 when in its upright position. It is evident that by 70 adjusting the positions of the set screws 65, the angle at which the frame 35 with its associated mirror 27 stands with regard to the light source and lens may be readily adjusted. The set screws 65 are easily accessible for such adjustment when the mirror 27 is swung backward to its horizontal 75 position.

A modified type of mirror retaining means has been shown in connection with Figs. 5 and 6, this means comprising two metallic strips 67 which are pivotally secured at their upper ends to the ears 75

36 of the mirror frame 35 by means of the machine screws 68. The strips 67 are provided with elongated slots 69 extending from their midpoints nearly to their lower extremities as shown. Two bolts 70 are threaded or otherwise rigidly secured in the side walls 71 of the bracket B', and are arranged to pass through the slots 69 in the strips 67, these bolts being provided with wing nuts 72 by means of which the strips 67 may be tightly clamped against the side walls 71 to firmly retain the mirror 27 in any desired angular position. When it is desired to clean or inspect the mirror 27, the light bulb 28 or the lens 22, the wing nuts 72 are loosened and the mirror is tilted backward, being held in a horizontal position by the strips 67 engaging the bolts 70 at the lower ends of the slots 69. After the required inspection, the mirror and frame are swung upwardly until the frame 35 engages the heads of the adjustable set screws 65, when the wing nuts 72 are again tightened, so retaining the mirror 27 and its frame 35 in their upright position.

A particular feature of the light signal comprising the present invention is the accessibility of the parts of its light projecting unit. When it is desired to clean or inspect the mirror and the light bulb, the door 9 is opened and the spring latches 41 are swung outward, allowing the mirror 27 to be swung backward for exposing the bulb 28 and the color screen 22. The mirror and the lenses may now be cleaned and the light bulb replaced without disturbing the focus adjustment. This accessibility of the light projecting unit parts is of great importance in railway signal

work as it reduces the time required for maintenance to a minimum.

As the color light signal comprising the present invention has been described in a rather specific form and in connection with a specific type of casing and supporting structure, it should be clearly understood that the invention is not limited in its scope to the particular structures shown, and that certain changes and modifications can be made without departing from the spirit of the invention as defined by the appended claims.

What it is desired to secure by Letters Patent is:—

1. In a light signal, in combination, a casing, a lens supporting ring secured to the casing, a lens in the ring, a shelf on the ring and extending into the casing, a light source, means for supporting the light source on the shelf, a concave reflector, means securing the reflector to the shelf, means for positioning the light source at the focal point of the reflector, and means for adjusting the reflector to project a beam through the lens.

2. In a light signal, in combination, a casing, a lens supporting ring secured to the casing, a lens in the ring, a shelf integral with the ring and extending into the casing, a light source, means for supporting the light source on the shelf, a concave reflector, means securing the reflector to the shelf, means for positioning the light source at the focal point of the reflector, and means for adjusting the reflector to project a beam through the lens.

SALISBURY M. DAY.
